(57) **CLAIM**

The ornamental design for an LED display screen with a quick installation structure, as shown and described.

DESCRIPTION

FIG. 1 is a front perspective view of the LED display screen with a quick installation structure showing my design.

FIG. 2 is a front elevation view thereof;

FIG. 3 is a back elevation view thereof;

FIG. 4 is a top plan view thereof;

FIG. 5 is a bottom view thereof;

FIG. 6 is a side elevation view thereof;

FIG. 7 is an opposite side elevation view thereof; and,

FIG. 8 is a rear perspective view thereof.

The broken line showing of an LED display screen with a quick installation structure is included for the purpose of illustrating portions of the article that form no part of the claimed design.

1 Claim, 5 Drawing Sheets
